TAKE-OFF DEVICE FOR LOOMS

William Simmons, New York, N. Y.

Application April 29, 1935, Serial No. 18,907

1 Claim. (Cl. 139—307)

This invention relates to take-off devices for use in conjunction with the take-up rollers of cloth weaving looms, particularly such looms upon which double pile fabric is woven.

5 A great deal of trouble is experienced at the take-up rolls of looms due to the tendency of the product to wind up on the same; when this happens, the loom must be stopped until the trouble is rectified, with a resulting loss of time. Moreover, the fabric is often damaged in correcting the trouble on account of the operator's haste, and especially so when the take-up roller is provided with radial pins on its periphery, the pins frequently tearing the product. The trouble mentioned is aggravated in the weaving of pile fabrics, which are woven double and then split by means of a knife; in such weaving there are two take-up rolls, one for each of the fabrics after splitting or cutting. It often happens that one of the split 10 parts of the product will continue to wind around its roll at a time when the other is running as it should. The part which continues to wind on its roll increases the virtual diameter of that roll and produces a tension greater than normal and thus 15 an unbalance in the tensions of the split pieces, which tensions should be equal, otherwise the knife employed to split the fabric, in cutting the pile, will cut the latter unevenly, and more on one side than on the other. My invention eliminates the foregoing difficulties and thus saves 20 time, and, what is more important, prevents damage to the product.

A further object of my invention is to provide 25 an efficient take-off device which may be used with equal facility on the various take-up rollers now in use by which to dependably engage the underside of the fabric issuing from the loom and to assure the positive and uniform operation of the take-off mechanism.

30 The invention will be fully and comprehensively understood from a consideration of the following detailed description when read in connection with the accompanying drawing which forms part of the application, with the understanding, however, that the improvement is capable of extended application and is not confined to the exact showing of the drawing nor to the precise construction described and, therefore, such changes and modifications may be made therein as do not affect the 35 spirit of the invention nor exceed the scope thereof as expressed in the appended claim.

In the drawing:

Fig. 1 is a side elevational diagrammatic view 40 with parts in section of a typical double pile fab-

ric weaving loom and incorporating my improved take-off device.

Fig. 2 is an enlarged side elevational view of my take-off device apart from the loom; and

Fig. 3 is a view similar to Fig. 2 but illustrating 5 a modified form of my device.

Referring now to the drawing for a more detailed description thereof and particularly to Fig. 1 which illustrates diagrammatically a typical double pile fabric loom, the numeral 4 indicates a 10 warp beam from which is fed the warp threads 5 or the fabric which pass over a guide rod 6 to be fed into the weaving mechanism 7 of the loom. Since the method of weaving double pile fabric is well known to those skilled in the art a detailed 15 description of same is not required. It will however be of assistance to note that as the warp threads pass thru the mechanism 7 other yarn is fed to the machine to form the pile of the fabric which is secured by weaving to the foundation of 20 same in cooperation with the action of the reciprocating shuttle. The double pile fabric thus woven is fed thru a pair of guide bars 8. It is to be noted here that the product at this stage of the process comprises upper and lower fabric 25 foundations which are connected by the pile threads 9 which, as the product issues from the bars 8, are severed by the knife 10 into two separate pile fabrics 11.

In order that the resultant fabrics be uniform- 30 ly severed by the knife 10 a uniform tension is applied to the fabrics 11 by the take-up rollers 12, the peripheries of which are provided with radial pins 13 which engage in the foundation of the fabric.

To assure the positive disengagement of the fabric from the pins 13 a belt 14 (see Fig. 2) is provided, which preferably extends the entire length of the roller 12. An idler roller 15 suitably journaled in the loom frame is arranged with its 40 axis parallel to the roller 12 so as to cause the belt 14 to leave and return to the periphery of the roller 12 on tangential lines. The belt 14 may be made of a loose woven fabric or other suitable material so as to permit the piercing of the pins 45 13 thru same, which pins project thru the outer surface of the belt 14 a sufficient length to adequately engage the fabric. As the fabric moves around the roller 12 to the point 16 at which it is to be disengaged from same, the tangential path of 50 the belt 14 assures the positive disengagement of the fabric from the pins 13. From the point 16 of the roller 12 the fabric is fed to a receiving roll.

Reference is now directed to the modified form 55 of my take-off device illustrated in Fig. 3 in which

the numeral 17 indicates a suitable take-up roller, to the periphery of which is affixed a sandpaper or other suitable rough surface 18. A take-off belt 19 travels on the roller 17 and is of a length sufficient to permit same to travel in a path substantially as illustrated. The belt 19 in this form is to be constructed of a suitably resilient material such as pliable leather or rubber, the outer surface of which is provided with a carborundum 10 coating or is otherwise suitably roughened to assure the frictional engagement with both the roller 17 and the woven fabric 20. In order that the belt 19 may grip the major portion of the periphery of the roller 17 an idler roller 21 is suitably arranged and is carried on a spring arm 22, which arm is so tensioned as to urge the roller 21 radially toward the axis of the roller 17. The spring arm 22 is suitably supported on the loom frame 23. The fabric 20 as it approaches the roller 17 is under tension so as to cause the belt 19 to travel on a tangential line toward the roller 17. As the fabric 20 moves around the roller 17 on the belt 19 to the point of discharge 24 the tangential path of the belt 19 resulting from the re-

sistence of same and also the arrangement of the idler roller 21 causes the fabric to leave the take-off mechanism in a tangential direction.

It will be apparent that the modified form of my take-off device shown in Fig. 3 may be used with equal facility in cooperation with a take-off roller provided with radial pins projecting from its surface, as shown in Fig. 2, in which instance the function of the belt 19 as described will assure the positive disengagement of the fabric 10 from the pins.

What is claimed as new is:

In a loom, the combination with a take-up roller having a plurality of radial pins for engagement with the fabric, an idler roller mounted in close proximity to said take-up roller, an endless belt thru which the pins of said take-up roller are adapted to pass and engage the fabric, said belt being extended around said take-up roller and over said idler roller to assure the positive disengagement of the fabric from the pins thereby preventing said fabric from winding completely around the roller.

WILLIAM SIMMONS.
